UNITED STATES PATENT OFFICE.

JOHN M. DALY, OF CHICAGO, ILLINOIS.

TONNAGE-EQUATING MACHINE.

939,222.

Specification of Letters Patent.

Patented Nov. 9, 1909.

Application filed January 4, 1906. Serial No. 294,662.

To all whom it may concern:

Be it known that I, JOHN M. DALY, a citizen of the United States, residing at Chicago, in the county of Cook and State 5 of Illinois, have invented certain new and useful Improvements in Tonnage-Equating Machines; and I do hereby declare that the following is a full, clear, and exact description of the invention, which will enable 10 others skilled in the art to which it appertains to make and use the same.

This invention has reference to a computing machine and relates particularly to a device for equating train tonnage or for 15 measuring the resistance of railway-trains.

One of the objects which I have in view with the present device in the equation of train tonnage, is to give an average allowance of draw-bar pull per car, thereby allowing the same to each weight of car next to the engine or caboose.

The results to be obtained by the present device is in most respects similar to that obtained by machines upon which patents 25 have already been granted to me and by others upon which applications for patent are now pending. The patents referred to are numbered 715,197 dated December 2, 1902; 715,199 dated December 2, 1902 and 715,201 30 dated December 2, 1902. The applications for patent to which reference has been made were filed on April 11th, 1904 and August 15th, 1905 and bear Serial Nos. 202,552; 202,553 and 274,342.

For a further and full description of the invention herein and the merits thereof, and also to acquire a knowledge of the details of construction of the means for effecting the result, reference is had to the following 40 description and drawings hereto attached.

While the essential and characteristic features of the invention are susceptible of modification, still the preferred embodiment of the invention is illustrated in the 45 accompanying drawings, in which:—

Figure 1 is a top plan view of a tonnage equating device embodying my improvements; Fig. 2 also shows a top plan view of my device and with the top plate or covering removed to show the relative arrangement of the working parts in the casing forming a part of said device; Fig. 3 is a cross section through the device, to illustrate in side elevation the mechanism which

controls the actuation of certain registering wheels, and known as the car numbering device; Fig. 4 is a cross section through the device to illustrate in side elevation certain trip mechanism and a gong, whereby in the operation of the device the gong is sounded 55 to indicate that the car limit in making up a train of cars has been reached; Fig. 5 is a cross section through the device, to illustrate in side elevation certain tonnage computing or registering wheels and coöperating parts; and also the car registering or tallying wheels and coöperative parts; Fig. 6 is a longitudinal and sectional detail through a portion of the device; a driving shaft and tonnage computing or registering 60 wheels in cross section on the said shaft; Fig. 7 is a longitudinal and sectional detail through a portion of the device; a shaft and car tallying or registering wheels in 65 cross section thereon, and Fig. 8 is a cross section taken through a portion of the casing of the said device and showing a revoluble wheel, disk or plate; a superposed plate or disk and the manner of mounting 70 both of said disks also a locking mechanism 75 carried by the superposed disk adapted to normally engage a part of the casing.

In the drawings like numerals of reference indicate corresponding parts throughout the figures.

1 refers generally to a casing having the side and end walls 2 and 3, the bottom 4 and a top or covering 5 which in this instance is shown having a detachable connection with the casing by means of the screws 6. The 85 said top or covering 5 is further provided with an annular cut out portion 7 and from the edge of the said cut out portion 7 the top is beveled rearwardly as at 8 to the surface thereof. At 9 the covering 5 is provided with a sight opening whereby an operator may readily see certain car tallying mechanism, to be described which is disposed in the casing beneath the opening 9 and at 10 is also shown a sight opening in the covering 5 90 whereby an operator may see certain tonnage computing or registering wheels disposed in the casing beneath the said opening. Extending up from the bottom 4, see Fig. 8, is shown a standard or upright 11 having a 95 reduced upper extension forming a shoulder 12 and the said standard is further provided with the interiorly threaded portion 13,

adapted to be engaged by the threaded screw or plug 14, whose office is to retain parts to be described in working position in the said casing and on the standard 11.

15 denotes an annular disk, plate or wheel which is adapted to be revolvably carried on the reduced upper extension of the standard 11 and to accomplish this the said disk is provided with the depending tubular portion 16 designed to be slipped over and encircle the standard 11 somewhat as seen in Fig. 8 and having its lower edge resting on the off set 12 of the standard 11. In working position the disk 15 is disposed in the 15 casing beneath the annular opening formed therein and the outer edge of the disk extends beyond the edge 7 forming the annular open way in the said casing. The disk 15 is further provided with the dependent 20 flange 17 projecting downwardly from the outer edge thereof and is provided with a series of teeth 18 extending around the entire lower edge of the flange 17.

19 indicates a series of perforations in the 25 disk 15 and are spaced, preferably equidistant to each other in a circumferential row around the disk.

20 denotes a superposed disk or annulus plate which is adapted to be rotatably held on 30 the upper end of the standard 11 by means of the screw or plug 14 which passes through an opening in the said plate and has a screw connection with the standard, as described. The disk 15 and the annulus plate 20 are 35 adapted to be held spaced apart, to permit of a free rotation of one or the other of said parts, for purposes which will be hereinafter apparent, and to separate the two parts I have provided the washer or interposed disk 40 21 which encircles the upper end of the standard 11, somewhat as seen in Fig. 8. The superposed annulus plate 20 has its outer peripheral edge located within the circle described by the series of perforations 45 19 arranged in the disk 15, and is spaced from the edge 7 of the covering 5 forming the wall of the cut out portion therein to provide the annular channel way 22 between the wall 7 and the peripheral edge of the 50 annulus plate 20, beneath which and corresponding to the annular channel way is disposed a series of perforations 19 in the disk 15.

The disk 15 is adapted to have a free rotation in opposite directions, while the annulus 55 plate is normally arranged stationary and locked in adjusted position, suitable locking means being provided which will now be described and the purposes of which hereinafter explained. On the annulus plate 20 60 at a suitable point is secured a block 23 which projects across the channel way 22 heretofore described and clearly seen in Fig. 8; the said block is provided with an open tubular chamber 24 which communicates 65 with a reduced longitudinal opening 25.

Operating in the longitudinal opening and chamber just described in the block 23 is a stem 26 on the rear end of which is carried a block or has formed thereon the head 27 provided with the depression or slot 28 projecting inwardly from the upper face thereof; and on the opposite end of the said stem and carried within the chamber 24 is a plug 29 between which and a shoulder formed by the wall of the chamber 24 and the longitudinal opening 25 is carried a coil spring 30 which encircles the said stem. The extreme outer end of the stem 26 when in normal position is adapted to engage with one of a series of slots 31 arranged in the 80 inner edge of a block 32, which may be attached to or form a part of the covering 5 of the said device. This block is of suitable width and length and in contour forms the segment of a circle so that the edge thereof in which the series of perforations 31 are arranged is on the same radius as the edge or wall 7 which forms the annular cut out portion of the covering 5.

It will readily be seen from the above description, taken in connection with Figs 1 and 8, that if it is desired to adjust or partially rotate the annulus plate 20 it is only necessary for the operator to insert a pointer or pencil of some suitable description into 90 the perforation or depression in the head 27 and drawing the same outwardly will disengage the end of the stem 26 from the perforation 31 with which it is then engaging in the block 32; upon the release of the 95 pencil or pointer from the head 27 the tension of the spring 30 against the plug 29 will force the stem 26 outwardly, and it in turn will engage with the desired perforation in the block 32; or if upon the release 100 of the stem 26 from the block 32 it is desired to place the annulus plate in a position for its disconnection from the casing or the standard 11 therein, the said plate will be rotated sufficiently to entirely disengage the 105 stem from the said block when, upon the removing of the screw or plug 14 the said annulus plate may be removed. It is adapted when rotating or partially rotating the 110 disk or plate 15, in a manner to be described, 115 to impart motion to a series of numbering wheels which are adapted to register train resistance computed by the actuation of the said disk in connection with an expanded and contracted scale; also to actuate certain 120 car tallying mechanism for registering the number of movements of the said disk 15, which movements correspond to the number of cars which are placed in a train the resistance of which it is desired to obtain; furthermore and in the operation of the disk 15 it is intended at a pre-determined number of operations thereof or when the car tallying mechanism has moved to a certain point 125 to signal by means of a gong that a given 130

number of cars have been placed in a train which indicates that the train limit has been reached.

Through the casing from one end thereof to the standard 11 is carried a shaft 33 which is journaled in a suitable bearing formed in the standard 11 and in the end wall of the casing, best seen in Figs. 2 and 6. Suitably secured on a shaft to rotate therewith is a pinion 34 which is in mesh with the teeth 18 of the depending flange of the disk 15, see Figs. 2 and 6 and carried on the said shaft between the end wall of the casing and the said pinion 34 is seen a series of registering wheels, forming respectively the unit, tenths, hundredths and thousandths wheels which together form the tonnage registering wheels of the device. Each of the wheels is provided with a series of numerals from "0" to "9." The units wheel is indicated as 35; the tenths wheel as 36; the hundredths wheel as 37 and the thousandths wheel as 38. The first mentioned wheel is adapted to be fixedly secured or attached to the shaft 33, see Figs. 2 and 6; while the remainder of the wheels, are all shown loosely carried on the said shaft.

The registering wheels 35, 36, 37 and 38 are not unlike registering wheels which are in general use in machines of this class and it is hardly thought necessary to describe the detail construction thereof, other than a general description to show how one of such wheels is capable of transmitting motion to its adjacent wheel. The units wheel 35 described as being secured on the shaft 33 is provided with a single tooth 39 projecting laterally therefrom, the same being substantially like that shown on the wheel 37 best seen in Fig. 5, the wheel 38 being broken away for the purpose of illustrating the same. With each movement of the shaft 33 the wheel 35 is correspondingly moved and with each complete rotation thereof the tooth 39 is adapted to engage with a tooth of a pinion 40 and move the said pinion the distance of one tooth. This pinion contains a series of teeth and each alternate tooth thereof is only half the width of the said pinion, for a purpose soon to become apparent. The wheels 36, 37 and 38 which are loose on the shaft are in most respects similar. That is, each of the said wheels is provided with the toothed portions 36^a, 37^a, and 38^a respectively, which extend completely around the periphery of the said wheels, and on the opposite sides of the wheels 36 and 37 only are provided single teeth 41 and 42, similar to the tooth 39 on the wheel 35 and each is adapted during a rotation thereof to engage with the tooth of a pinion 43 and 44 for the purpose of moving the said pinions the distance of one tooth during each revolution of the said 65 wheels. For a better understanding of the

operation of the registering wheels it is understood that through the movement of the disk 15 the shaft 33 is actuated through the pinion 34 and through such movement of the shaft the units wheel 35 is also rotated. When the units wheel makes a complete rotation its tooth 39 engages with the pinion 40 and moves it the distance of one tooth; the toothed portion 36^a of the wheel 36 is continuously in mesh with the pinion 40 and when the latter is moved the distance of one tooth it will be seen that the wheel 36 is moved the distance of one tooth. The wheels 37 and 38 have their toothed portions 37^a and 38^a in mesh with the pinions 43 and 44, so that with each rotation of the wheel 36 its tooth 41 will move the pinion 43 the distance of a tooth and it in turn will move the wheel 47 the distance of one tooth; and when the last mentioned wheel has made one revolution its tooth 42 will engage with the pinion 44 and move it the distance of one tooth and it in turn will move the wheel 38 the distance of one tooth.

In connection with the perforated disk 15 I have provided a scale or chart and the same is indicated as a whole, as 45. This scale or chart is preferably placed on the inclined face 8 of the covering 5 and the characters which go to make up the said scale are arranged opposite a perforation 19 in the rotatable disk 15. The designating characters are preferably numerals and the said scale has both, a contracted and expanded portion. The contracted portion being that portion of the scale between "1" and "40" and the expanded portion of the scale is that part between the numeral "40" and "75". The arrangement of the numerals which go to make up the scale is from "1" to "75" and is sufficient to illustrate the principle involved and the mode or system of reducing train tonnage to train resistance; although, the scale or chart might be continued to a greater length if it is so desired. The numerals of the scale or chart are designed to indicate tons in car, as called for by the way-bill or manifest, and like in the patents and applications for patent referred to the scale is based on a testing unit and the particular scale seen in Fig. 1 of the drawings is adapted for use in computing the train resistance on an engine which is rated at two thousand (2000) tons and wherein the unit of such rating is a forty (40) ton car; and said scale, as will be further explained is expanded for cars of less than forty (40) tons and contracted for cars of more than forty (40) tons. One of the methods by which this rating is found is fully explained in the patent issued to me and heretofore referred to as Number 715,199, dated December the 2nd 1902.

In connection with the scale or chart re-

70

ferred to and the perforated disk 15 coöperating therewith I have provided an adjustable feature, expanded scale or allowance, whereby the machine or device may be adjusted to compute the resistance of cars when employing the said device for engines of different sizes and capacity; this will obviate the necessity of having to have a series of different machines in each office adjusted to different sizes and capacity of engines. In this way, I not only provide an average basis for a train with heavy and light cars mixed, wherein there is conceded weight to the light cars and shrink the weight on heavy cars, but also makes an allowance to engines in proportion to their rating.

The adjustable feature, expanded scale or allowance is employed on the device in connection with the yieldingly held stem 26 and the block 32 of the covering having the series of perforations 31 extending into the said block. On the upper face of the block is provided a scale or chart indicated generally as 46 and made up of the following: "300 to 999"; "1000 to 1999"; "2000 to 2999"; and "3000 to 5000". These characters indicate the different sizes and capacity of engines within the rating provided for by this scale or chart 46. The first is used in connection with the size or capacity of an engine between 300 and 900 tons; the second is used in connection with the size or capacity of an engine between 1000 and 1999 tons; the third is used in connection with the size and capacity of an engine between 2000 and 2999 tons and the last is used in connection with the size and capacity of an engine between 3000 and 5000 tons. In the adjustment shown in Fig. 1 of the stem 26 engaging a perforation 31 in the block 32 the machine is being used for the placing of cars in a train, the engine hauling which has the rating of two thousand (2000) tons. If it were desired to use the device in connection with an engine whose rating was anything between 300 and 999 tons the head 27 of the stem 26 would be withdrawn for the purpose of partially rotating the superposed plate 20 whereby the stem would be caused to be inserted in a perforation 31 of the block 32 coinciding with the characters or numerals "300" to "999"; or if the rating of the engine were between 1000 and 1999 tons or between 3000 and 5000 tons the adjustment of the superposed plate and the stem 26 would be substantially as that just above described. It is to be noted that the forward portion of the block or member 23 extends across the channel way 22 formed by the covering 5 and the superposed plate 20 and is in width at this point to extend across one perforation only in the disk 15. In this way, a pin, stem or suitable pencil inserted at any point into one of the perforations of the disk 15 and rotating the disk in the direction indi-

cated by the arrow in Fig. 1, the said pin, stem or pencil will engage with the outside wall of that portion of the block or member 23 crossing the channel 22, just above described.

The arrangement of the scale or chart 45 on the inclined face 8 of the covering 5 is such, that on a rating of 2000 tons where the unit is a forty (40) ton car, the numeral 1 or the first character of the scale will be removed or spaced from the two thousand (2000) ton mark on the block 32 so that if a stem were placed in the perforation 19 of the disk 15 opposite the "40" ton mark and the disk rotated until the pin engaged with the block 23 the tonnage registering mechanism, consisting of the wheels heretofore described would indicate thereon "40" tons which would be readable through the sight opening 10 in the covering 5.

The scale or chart 45 has been referred to as being expanded below the unit and contracted above the same. It is believed that this is readily seen in connection with the above description relating to the tonnage scale or chart indicated as 45 and the adjustable feature expanded scale or allowance indicated on the chart 46 and the disk position or placing of the first character of the tonnage scale or chart 45 with reference to the "2000" ton rating appearing on the chart 46, by which provision is made for the registration of forty (40) tons between the "40" ton mark on the scale 45 and the block 23 when the same is in alinement with the "2000" tons appearing on the chart 46.

In connection with the variable features of the scale or chart 46 and the stem 26 coöperating therewith a "15" ton car placed in a train rated at "300" to "999" tons the registering mechanism will indicate, instead of "15" tons, "17" tons; and the same car put into a train rated at "3000" to "5000" tons, the registering mechanism, instead of registering "15" tons will register "20" tons. This it is believed fully illustrates the expandible feature of all cars placed into a train, where the cars are of less than of forty (40) tons. Now then, a "70" ton car placed in a train rated at "300" to "999" tons, the registering mechanism instead of registering "70" tons will register "55" tons and the same car placed in a train rated at "3000" to "5000" tons, the registering mechanism instead of registering the amount indicated by the way-bill or manifest or the character on the scale 45 corresponding to the tons in car appearing on the way-bill or manifest, will register "57" tons. This it is believed fully illustrated the contractible feature of all cars placed into a train, where the cars are of more than forty (40) tons.

The difference in allowance made on same gross weight of car is due to the capacity of

engine, viz: an engine rated "300 to 999" tons is only required to haul approximately from eight (8) to sixteen (16) cars to obtain this rating in gross tons; whereas to haul "3000 to 5000" tons engine must haul approximately fifty (50) to seventy-five (75) cars. With a small train less cars bind in the curves and there is less wind resistance. Again, on momentum grades, a short train of from ten (10) to fifteen (15) cars, allows the engine to get a run at the next grade; whereas, a long train holds back and forces the engine to work hard down the first hill to pull the rear part of the train up hill. Hence an engine can come nearer to hauling its full rating of light cars on a "300 to 999" ton rating, than it can on a "3000 to 5000" ton rating, and for this reason I make a greater allowance as the rating increases, which is accomplished by means of the block 23 and its component parts.

The car tallying mechanism which has been referred to will now be described. There extends longitudinally through the casing 1 a shaft 47 on one end of which and within the casing is provided a pair of numbering wheels 48 and 49 adapted to tally each movement of the disk 15 and thereby register the number of cars placed in a train. The wheels 48 and 49 are in all respects similar to wheels 37 and 38 of the tonnage registering mechanism. That is each is provided with the toothed portions 48^a and 49^a respectively which extend completely around the periphery of the said wheels on one edge thereof; and on the opposite side of the wheel 48 at a suitable point is provided the single laterally projecting tooth 50, which is similar to the tooth 39 on the wheel 35 and the corresponding teeth of the wheels 36 and 37. It is adapted in the rotation of the wheel 48, or during each revolution thereof that the tooth 50 will engage with a tooth of the pinion 51, with which the teeth of the wheel 49 are constantly in mesh and with each revolution of the wheel 48 the tooth 50 thereof will move the pinion 51 the distance of one tooth which in turn will move the wheel 49 the distance of one tooth. The pinion 51 is in all respects similar to the pinion 40, wherein the alternate teeth are only half the width of the said pinion. The wheel 48 is keyed or otherwise suitably secured to the shaft 47, preferably by a spline and grooved connection, the spline being indicated as 52 and best seen in Fig. 7. The wheel 49 is slidably carried on the shaft 47 and has the extended hub portion 53 to which is attached one end of a flat coil spring 53^a which is coiled concentrically about the axis of the shaft 47 and has its opposite end secured to a rod 54, see Fig. 5, on which the pinion 51 is journaled and which is secured in the frame of the machine.

The rod 54 has attached thereto a short

vertical standard 55, see Fig. 5, which is placed in close proximity to the outer face of the wheel 49 and the upper end of the standard 55 is in such a position that a pin 56 secured to and projecting from the wheel 49, when the parts are in a normal position or both of the tallying wheels at "0," will rest on the upper end of the standard 55, substantially as seen in Fig. 5. The continuous rotation of the wheel 49 in the direction of the arrow shown on the said wheel in Fig. 5 will wind up the spring 53^a and cause the pin 56 to engage a depression or slot 57 in the standard 55, this will lock the parts in an immovable position. For the purpose of releasing the tallying wheel 49 so as to disengage the teeth thereof from the teeth of the pinion 51 to permit the spring 53^a to automatically return the wheel 49 to its initial position which will return the pin 56 from the notch 57 in the standard 55 to again rest on the standard, as seen in Fig. 5, I have provided for projecting the shaft 47 in the direction shown by the arrow in Fig. 7 and by such movement the spline 52 of the shaft will engage with the face of the wheel 49 and projecting it longitudinally with the shaft until the teeth 49^a of the wheel 49 are disengaged from the pinion 51 which will permit of the spring 53^a exerting its pressure to return the wheel 49 to its normal position, as there is nothing to prevent the return of the said wheel under the pressure of the said spring after the teeth of the wheel have been disengaged from the pinion. A finger hole 58 is provided on the outer end of the shaft 47, see Fig. 2, which enables the operator to project the shaft 47 in the manner described. On the shaft is a collar 59 and between said collar and the wheel 48 is a spring 60 encircling the shaft, which, after the return of the wheel 49 to its initial position will return the shaft 47 to its normal position through the pressure on the collar 59. And on a reduced portion 61 of the shaft 47 is carried a coil spring 62 which bears against the end wall 3 of the casing and the end of the sleeve of the wheel 49; its office being to act upon the sleeve of the said wheel for the purpose of returning the wheel 49 in a position where the teeth thereof will engage with the pinion 51, after the said wheel has returned to "0". It is believed it will be understood how the wheel 49 returns to its initial position when the shaft 47 is projected, to correspondingly return the wheel 48 to its initial position, the operator through the finger hole 58 will turn the shaft 47 and thereby place the wheel 48 in its desired position.

The manner of operating the shaft 47 for illustrating on the tallying wheels 48 and 49 the number of cars placed in the train which corresponds to the number of

movements imparted to the disk 15 will now be described. On the shaft 47, see Fig. 3, is carried a ratchet wheel 63 which is adapted to have movement imparted thereto in the direction indicated by the arrow in said figure. For imparting a step by step movement to the ratchet wheel 63 I have provided a spring arm 64 adapted to engage with the teeth of the said wheel and the spring arm is secured at one end to an arm 65 which is fulcrumed on the shaft 47. Adjacent to the arm 65 is carried a stem 66 disposed in a vertical position in the said casing and on the upper end of the said stem is secured a crank arm 67 which is carried across the face of the disk 15 and beneath the superposed plate 20, for a purpose to be described. Attached to the stem 66 and projecting outwardly therefrom is a finger 68, which, when the crank arm 67 is actuated and in turn partially rotates the stem 66, will engage a cam face 69 of the arm 65 and elevating the lower end of said arm will cause the spring arm 64 to move the ratchet wheel 63 the distance of one tooth, which in turn, will partially rotate the shaft 47 and correspondingly the wheel 48. A coil spring 70 carried on the stem 66 and having its ends suitably secured is adapted to automatically return the stem 66 with its crank arm 67 to its initial position and allow the arm 65 to drop and place the end of the spring arm 64 in a position to engage the next tooth of the ratchet wheel 63. To limit the return movement of the stem 66 and operate the crank arm 67 thereof, I have provided the pin 71, shown in dotted lines in Fig. 1, which depends from the covering 5 and is engaged by the crank arm 67 somewhat as shown in Fig. 1.

To operate the crank arm 67 for rotating the stem 66 to impart movement to the shaft 47 in the manner heretofore described, the movement of the disk 15 by means of a suitable stem or pencil inserted in one of the perforations 19 and moved through the channel way 22, when the said stem or pencil engages with the free end of the crank arm 67 which lies across the upper face of the disk 15 and also the channel way 22, it will be seen that the said crank arm will be oscillated and by such movement through the pin 68 from the stem 66 elevate the arm 65 for imparting a partial rotation to the ratchet wheel 63 through the spring arm 64 and when the stem or pencil moves off of the end of the crank arm 67, the spring 70 operates to return the stem 66 and the crank arm 67 to their initial position.

I have provided in connection with the car tallying mechanism and the shaft 47 a gong and a trip feature for signaling the gong at pre-determined intervals in the operation of the machine to indicate to the operator that a given number of cars has been

placed in a train and that the train limit of cars has been reached. A train limit consists approximately of 60 or 70 cars and to notify the operator when 60 cars have been placed in a train I have provided the bell 72 suitably supported by or on the base of the machine and 73 denotes a longitudinally carried and rocking shaft or rod 73 journaled in the bracket 74 projecting inwardly from the sides of the casing 1. On one end of this shaft or rod is carried a trip arm 75 which engages with the end of a lever 76 fulcrumed at 77 to a suitable support 78 extending up from the base of the casing and the outer free end of the lever 76 is adapted to engage with one end of a bell crank lever 79 pivotally supported at 80 to a stem 81 projecting inwardly from the end of the casing, and on the lower end of the opposite extension of the bell crank lever 85 is provided a knob 82 adapted to engage or strike the bell 72. On the opposite end of the shaft or rod 73 to that which carries the trip arm 75, is carried a second trip arm 83 which projects inwardly and alongside of one of the car tallying wheels and preferably the wheel indicated as 49.

In the rotation of the wheel 49 just referred to, it is adapted to have the pin 56 heretofore referred to, engage with the trip arm 83 and depressing the same partially rotates or rocks the shaft or rod 73 and by such movement the trip arm 75 will actuate the lever 76 and it in turn will elevate the knob end 82 of the bell crank lever 79. Upon the pin 56 riding off of the trip arm 83 a spring 84 attached to the free end of the lever 76 and also to the support 78 will automatically lower the free end of the lever 76 and elevate its opposite end, which, engaging with the trip arm 75 will return it together with the shaft or rod 73 and the trip arm 83 to their normal position, and simultaneous with the return of such parts the knob 82 of the bell crank lever 79 will sound the gong by engaging with the bell 72.

In Fig. 4 the lever 76, the bell 72 and their component parts are shown in two different positions. In Fig. 5 the trip arm 83 is also shown in two different positions, and also the manner in which the pin 56 engages with the same for depressing the said trip arm to actuate the rock shaft or rod 73 for sounding the gong in the manner described when the train limit has been reached. The pin 56 is so positioned on the wheel 49, that when the wheels 48 and 49 have moved to a position to register 60, the said pin 56 will trip the arm 83 to sound the said gong.

I have described in connection with the tonnage resistance computing wheels 35, 36, 37 and 38 the means by which the same are successively actuated and together with the scales of the device how the actual tonnage of a train is reduced to train resistance. I

will now proceed to describe means by which the tonnage registering wheels are returned to their initial position. The wheels 36, 37 and 38 have pivotally attached to their side faces the pawls 85, see Figs. 2, 5 and 6 and the said pawls are adapted to have engagement with a longitudinal slot or groove 86 in the shaft 33. And 87 denote flat springs which are secured to short sleeves or hubs of the said wheels and the free ends of the springs engage with the pawls 85, somewhat as seen in Fig. 5.

A cradle consisting of the plate 88 and the side arms 89 is pivotally connected at 90 to one of the sides of the casing 1 and normally held in an elevated position by a flat spring 91 secured at 92 to the side 2 of the casing and engaging with the lower face of the plate 88. The pinions 40, 43 and 44 which have heretofore been referred to as being engaged by the tonnage registering wheels are all carried by a short spindle 93 journaled in the free ends of the side arms 89, see Fig. 5. The forward end of the plate 88 is covered with felt or some other suitable material 94 and when the plate 88 is depressed, in a manner to be described the felt face 94 of the said plate 88 will engage with the peripheral faces of the registering wheels for the purpose of holding the said wheels steady while the said wheels are being returned to "0". It will be seen that if the plate 88 is depressed, so will the side arms 89 be depressed and disengage the pinions carried by said arms from the registering wheels and to retain the pinions in their relative positions in which they leave the registering wheels when the cradle is depressed I have provided a V shaped trough 95 which is suitably secured on the bottom of the casing 1 beneath the pinions carried by the arms 89, so that when the cradle is lowered the pinions will engage with the trough and be locked against rotation or accidental displacement, so that when the cradle is again raised the pinions will be in a position to properly engage with the registering wheels aforesaid.

The direction of movement of the tonnage registering wheels when train resistance is being computed will be in the direction of the arrow shown on wheel 38 in Fig. 5; but when it is adapted to return the said wheels to their initial positions at "0" the direction of rotation will be just opposite to that just described and the returning of said wheels being accomplished through the movement of the disk 15 it is natural to suppose that the disk 15 must be rotated in a direction opposite to that above referred to and is indicated by the arrow in Fig. 1. To accomplish this return of the wheels to their initial position the operator will press down on a stem 66 attached to the upper face of the plate 88 of the cradle, which ex-

tends up through an opening 97 in the covering 5. Through this movement of the scale 96 the cradle will be depressed to engage with the registering wheels and to also disengage the pinions carried by the cradle from said wheels, in the manner described. The pointer or pencil used for actuating the disk 15 will then be inserted in one of the holes and a reverse movement imparted to the said disk, which, through its engagement of the pin 34 on the shaft 33 also impart a reverse movement to the said shaft and the registering wheels carried thereby. And a pin 98 which projects outwardly from the face of the wheel 38 will engage with the extension 99 of a tumbler-pawl 100 pivoted at 101 to the forward end of the plate 88 of the cradle, and through such engagement of the pin 98 with the extension 99 of the said tumbler-pawl, the latter will be slightly oscillated on its pivot sufficient to lower the extension 102 of the tumbler-pawl into the path of movement of the pin 98 to engage the same in the further rotation of the said wheel 38 and prevent any further movement of said wheel 38 which at this time will be in its initial position or with the "0" beneath the sight opening 10 in the covering 5. With this position of the wheel 38 and its pawl engaging with the slot or groove in the shaft 33, in the further rotation of the said shaft through the movement of the disk the remainder of the registering wheels will be gathered or returned to their initial positions and their pawls enter the slot or the groove in the shaft 33 when the entire series of registering wheels will be in corresponding positions ready to begin a new operation. Upon the release of the stem 96 the spring 91 will automatically return the cradle and its parts to their normal positions, and as a means of controlling the movement of the tumbler-pawl upon the first engagement thereon by the pin 98 I have provided the pin 103, adapted to engage the said pawl in the manner seen in Fig. 5.

In Fig. 1 I have shown the preferred arrangement of scale or chart which is placed on the bevel face 8 of the covering 5, and by the same I am enabled to reduce train tonnage to train resistance. As was above described all cars placed in a train of less than forty (40) tons are expanded and all cars of more than forty (40) tons are contracted. So that on the basis of 2000 ton rating and a forty (40) ton unit a train made up of fifty (50) cars, of forty (40) tons each, 2000 tons will be registered on the registering mechanism. And if the train is made up of 83 cars, of 20 tons each, 1660 tons will be registered on the registering mechanism or if the train is made up of 36 cars, of 70 tons each, 2520 tons will be registered on the registering mechanism.

The perforations 19 in the disk 15 repre-

130

sent one tooth each of the toothed portion of the said disk or are disposed in the said disk to coincide with the teeth thereof, and each perforation or each tooth represent one ton.

5 So that if the stem 26 of the block 23 coincide with 2000 tons, between the said block and the "40" of scale 45 there will be 40 perforations, equaling 40 tons. And the scale 45 between "1" and "40" has been

10 contracted as is readily seen by doubling the characters at certain points for the purpose of equating the proper resistance to cars below the unit when the resistance thereof is computed in connection with the scale 46 in

15 manner described; and likewise that portion of the scale above the unit or "40" ton mark is contracted but in a greater proportion than that shown on the portion of the scale below the unit for the purpose of equating

20 the proper resistance to cars above the unit. Thus it will be seen that the adjustment of the scale 46 to the scale 45 permits of the hauling of a greater tons resistance in heavy cars than is permitted in light cars. And

25 to give a better understanding of such equation of tonnage resistance, and particularly on an engine rated at 2000 tons, the said engine will haul only 1660 tons of 20 ton cars, 1890 tons of 30 ton cars and 2000 tons of 40

30 ton cars which is the unit of rating; while the same engine will haul 2120 tons of 50 ton cars, 2310 tons of 60 ton cars or 2520 tons of 70 ton cars. This it is believed has been fully explained in connection with the

35 scale 45, wherein a 20 ton car measures 24 ton resistance; a 30 ton car, 32 tons resistance while a 40 ton car being the unit of rating measures 40 tons; a 50 ton car measures 47 tons resistance; a 60 ton car, 52 tons resistance and a 70 ton car 56 tons resistance.

40 The above have been selected at random, but a careful examination of Fig. 1 will substantiate this showing.

By beveling the covering 5 as at 8 and placing the scale 45 thereon it brings the characters of the scale in close proximity to the perforations in the disk 15 so that there is little danger of the operator making a mistake when placing a pointer or pencil into a perforation of the said disk alongside of a character designating tons in car, the resistance of which is to be computed.

Attention is here called to the fact that in computing the resistance in trains of cars, the pointer or pencil used to operate the disk 15 will be inserted into the perforation in the disk opposite the number on the scale corresponding to the tons called for by the way-bill or manifest, but through the mechanism described as coöperating with the said scale and disk the tonnage registering wheels will register amounts at variance with that called for on the scale, or in fact reducing tonnage to train resistance.

Having thus fully described my invention 65 what I claim and desire to secure by Letters Patent of the United States, is:—

1. In a device of the character described, registering mechanism, comprising a plurality of numbering wheels registering in uniform sequence, means for operating said mechanism, a member having a scale associated with said register operating means and serving as a guide to the operation of the same, and an adjustable member serving as 75 a stop to limit the movement given to the register operating means.

2. A device for computing tonnage resistance of railway trains, comprising registering mechanism, means for operating said 80 mechanism, a member having a series of indicating points comprising a tonnage scale, said series of points being marked by numbers serving as a guide in operating the registering mechanism by the operating means, 85 and an adjustable member serving both as a means of limiting the movement given to the register operating means and as a guide for the computation of the resistance of trains hauled by engines having a different 90 rating.

3. A device for computing tonnage resistance of railway trains, comprising registering mechanism, means for operating said 95 mechanism, a member having a scale, said scale serving as a guide to the operation of the register operating means, an adjustable member serving both as a means of limiting the movement given to the register operating means and as a guide for the computation 100 of the resistance of trains hauled by engines having a different rating.

4. In a computing machine, the combination with adding devices and means for operating the same, a numerical scale adjusted 105 to a unit of rating and associated with said operating means, the numerals thereon representing gross weights of cars and contents, and means coöperating with the numbers on the scale and serving as a stop for the operating means, whereby when the operating means is moved from a point opposite certain numerals on the scale representing cars of less gross weight than the rating unit, to the stop, the adding devices will register an 110 amount greater than said numerals, and when the operating means is moved from a point opposite certain numerals on the scale representing cars of a greater gross weight than the rating unit, to the stop, the adding 115 device will register an amount less than said numerals.

5. In a device of the character described, the combination with register operating means, of a member containing a scale composed of characters based on a unit of rating, 125 a rating chart associated with said scale, and a stop member for limiting the movement

given to the register operating means, said stop member being arranged to coöperate with said rating chart.

6. In a computing machine, the combination with suitable registering devices, of a rotating disk for operating said registering devices, a numerical scale adjusted on a unit of rating and located in juxtaposition to said disk, the numerals thereon representing gross weights of cars and contents, and means coöoperating with the numbers on the scale and serving as a stop for the movement of the disk, whereby when the disk is operated from a point opposite a certain number of approximately less than the rating unit, to the stop, the register will be caused to add an amount greater than the number appearing on the scale, and when said disk is operated from a point opposite a certain number of approximately greater than the rating unit, to the stop, the register will be caused to add an amount less than the number appearing on the scale, and when said disk is operated from a point opposite a certain number of approximately the rating unit, to the stop, the register will be caused to add an amount equal to the number appearing on the scale.

7. A device for computing the tonnage resistance of railway trains, comprising a register for displaying train resistance when computed, a member containing a scale based on a unit of rating and having characters to represent tons in cars, register operating means associated with said scale and operated from any point opposite the characters on said scale, and means adjustable with respect to said scale for limiting the movement given to register operated means, the adjustment of said last mentioned means changing the result displayed by said register upon the operation thereof from various points opposite said scale.

8. In a computing machine, the combination of a suitable registering device, a disk connected with said registering device and capable of being operated by a stylus, a ring like member disposed in juxtaposition to the disk and having a series of indicating points comprising a tonnage scale, said series of points being marked by numbers, and a stop member for the disk arranged at a suitable distance in advance of the beginning of said scale.

55. 9. In a computing machine, the combination of a suitable registering device, a disk connected with said registering device and capable of being operated by a stylus, a ring like member disposed in juxtaposition to the disk and having a series of indicating points comprising a tonnage scale, said series of points being marked by numbers, a stop member for the disk arranged at a suitable distance in advance of the beginning of said

scale, and means for adjusting said stop member toward and from the scale.

10. In a device of the character described, the combination of a revoluble disk provided with a plurality of perforations into which means may be inserted for operating the disk, a scale extending around a portion of the disk, the same composed of a series of characters based on a unit of rating, with each character of the scale opposite a perforation in the disk, and said scale opposite certain of said perforations in the disk, having a plurality of different characters coinciding therewith, mechanism operated by the disk during each movement thereof from points opposite certain portions of said scale for registering amounts at variance to that called for by the scale, and car tallying mechanism adapted to be also operated by said disk.

11. In a device of the character described, the combination of a revolably mounted disk, a scale associated with the disk and composed of characters based on a unit of rating, a rating chart associated with the scale, a member associated with the chart and adjustable with respect thereto, whereby the device may be used to compute the resistance of cars for engines of different sizes and capacity, mechanism operated by the disk for registering such resistance, and mechanism also operated by the disk for tallying the movements thereof.

12. A device for computing the tonnage resistance of railway trains, comprising registering mechanism, means for operating said mechanism, members having fixed scales, and a stop adapted to have an adjustable connection with the member having one of said scales, whereby computation with the other of said scales may be varied.

13. A device for computing the tonnage resistance of railway trains, comprising registering mechanism, means for operating said mechanism, a member having a fixed scale, an adjustable stop associated with said scale, and means for tallying each movement of the registering mechanism.

14. A device for computing the tonnage resistance of railway trains, comprising a plurality of coöperating numbering wheels, a disk for operating said wheels, a member having a fixed scale, a chart for indicating sizes and capacities of engines in connection with which said scale may be used, and an adjustable stop for limiting the movement given to the disk.

15. A device for computing the tonnage resistance of railway trains, comprising a plurality of coöperating numbering wheels, a disk for operating said wheels, a member having a fixed scale, a chart for indicating sizes and capacities of engines in connection with which said scales may be used, an ad-

justable stop for limiting the movement given to the disk, and means for tallying the movements of the disk.

16. In a device of the character described, 5 the combination of a plurality of numbering wheels, gearing connecting the numbering wheels, a disk for advancing said numbering wheels, means for releasing the gearing from the numbering wheels that they may be 10 turned by said disk, a member having a scale, an adjustable stop for limiting the movement given to the disk and means for tallying the forward movements of the disk.

17. In a device of the character described, 15 the combination of a plurality of coöperating registering wheels, a plurality of tallying wheels, a rotatably supported disk, connections between the disk and registering wheels, means operated through each movement of the disk for operating the tallying 20 wheels, and an adjustable stop for limiting the movement given to the disk.

18. In a device of the character described, 25 the combination of a plurality of coöperating registering wheels, a plurality of tallying wheels, a rotatably supported disk, connections between the disk and registering wheels, means operated through each movement of the disk for operating the tallying 30 wheels, a member having a fixed scale, a chart for indicating sizes and capacities of engines in connection with which said scale may be used, and an adjustable stop for limiting the movement given to the disk.

35 19. In a device of the character described, the combination of a plurality of coöperating registering wheels, a member having attached thereto a scale, a disk provided with a plurality of perforations coöperating with 40 said scale, connections between the disks and registering wheels, a movable stop member for limiting the movement given to the disk, a tallying device, and means operated through each movement of the disk for operating said tallying device.

50 20. In a device of the character described, the combination of registering mechanism, means for operating said mechanism, and a scale so adjusted with respect to said registering operating means, that with each operation of said registering mechanism from 55 points opposite certain portions of said scale, the same will add and display amounts, more or less than called for by the numerals on the scale.

21. In a device of the character described, 60 the combination of a scale consisting of numerals representing gross tons of cars and contents, registering mechanism, and means associated with said scale, capable of being operated from points opposite any numeral thereon for actuating said registering mechanism, said register operating means when operated from points opposite certain portions of said scale, causing the register to

add and display an amount at variance to that called for by the number of said scale, said amount displayed being equal to the draw-bar pull of the car and contents.

22. In a device of the character described, 70 75 the combination of registering mechanism, a revoluble plate capable of operating said mechanism when rotated, a scale coöperating with said plate and consisting of numerals representing gross tons of cars and contents, the operation of the plate from points opposite certain portions of said scale causing the registering mechanism to add, and display an amount at variance to that called for by the number on the scale, being equal to the 80 draw-bar pull of the car and contents.

23. In a device of the character described, the combination of a scale consisting of numerals representing gross-tons of cars and contents, a chart for regulating said device 85 in connection with engines having different ratings, a member coöperating with scale and chart and capable of operating said registering mechanism, means in connection with the chart for limiting the movement given 90 to the member, the operation of said member from points opposite certain portions of said scale causing the registering mechanism to add, and display an amount at variance to that called for by the number on said scale, 95 being equal to the draw bar pull of the cars and contents.

24. In a device of the character described, the combination of a scale consisting of numerals representing gross-tons of cars and 100 contents, a chart for regulating said device in connection with engines having different ratings, a revoluble plate coöperating with said scale and capable of operating said registering mechanism, means in connection 105 with the chart for limiting the movement given to the plate, means for engaging said plate coincident with any of the numerals of the scale, for operating said plate, the operation of the plate from points opposite certain portions of said scale causing the registering mechanism to add, and display an amount at variance to that called for by the number on said scale, being equal to the 110 draw-bar pull of the cars and contents.

25. In a device of the character described, 115 the combination of registering mechanism, a revoluble plate operatively connected with said mechanism, a scale associated with said plate and serving as a guide to the operation of the plate, said scale based on a unit of rating and consisting of numerals representing gross tons of cars and contents, the operation of the plate from various points opposite said scale causing the 120 registering mechanism to add and display an amount equal to the draw-bar pull of car and contents, and when operated from certain points in front of the unit mark of the scale, to cause the registering mechanism 125 130

to register an amount greater than the number on the scale, and said plate when operated from certain points opposite said scale behind the unit mark thereof, causing said registering mechanism to register an amount less than the number on the scale.

26. A computing machine, comprising registering mechanism consisting of a plurality of numbering wheels, a revolute plate, 10 gearing interposed between said plate and numbering wheels, the operation of said plate in one direction causing said numbering wheels to register, and mechanism for causing said numbering wheels to return to 15 their initial position when said revolving plate is reversed.

27. A computing machine, comprising a plurality of numbering wheels, gearing connecting said numbering wheels, a revolute 20 plate, gearing connecting said plate with said numbering wheels, the operation of said plate in one direction causing said numbering wheels to register, and means for releasing the gearing connecting the plurality of 25 numbering wheels, to allow said numbering wheels to be returned to their initial position when said revolute plate is reversed.

28. A computing machine, comprising a plurality of numbering wheels, gearing connecting said numbering wheels, a revolute 30 plate, gearing connecting said plate with said numbering wheels, a member associated with said plate containing a scale composed of a series of numerals, the operation of said 35 plate in one direction from a point coincident with any of the numbers of said scale, causing the numbering wheels to register, and means for regulating the gearing connecting the numbering wheels, so as to allow 40 said numbering wheels to be returned to their initial position when the revolute plate is reversed.

29. A computing machine, comprising a plurality of numbering wheels, gearing connecting said numbering wheels, a revolute 45 plate, gearing connecting said plate with said numbering wheels, a member associated with said plate containing a scale composed of a series of numerals, the operation of said 50 plate in one direction from a point coincident with any of the numbers of said scale, causing the numbering wheels to register, and compressible means associated with the gearing connecting the numbering wheels for 55 releasing the same from said numbering wheels, whereby said numbering wheels may be returned to their initial position when the revolute plate is reversed.

30. A computing machine, comprising a 60 plurality of numbering wheels, gearing connecting said numbering wheels, and means associated therewith, for locking said numbering wheels against a reverse motion, a revolute plate, gearing connecting said 65 plate with said numbering wheels, the oper-

ation of said plate in one direction causing said numbering wheels to register, and means for releasing the numbering wheels from said gearing and locking means associated therewith, whereby said numbering 70 wheels may be returned to their initial position upon a reversal of the operation of said plate.

31. A computing machine, comprising a plurality of numbering wheels, gearing connecting said numbering wheels, a revolute plate, connections between said plate and numbering wheels, means for releasing the gearing connecting the numbering wheels, whereby said numbering wheels may be returned to their initial position upon a reversal of the operation of said plate, and interconnected means between said numbering wheels for successively returning the same to such initial position upon the operation of the plate as aforesaid.

32. A computing machine, comprising a plurality of numbering wheels, gearing connecting said numbering wheels, a revolute plate provided with a plurality of perforations for the insertion of a stylus for operating said plate, connections between said plate and numbering wheels, means for releasing the gearing connecting the numbering wheels, whereby they may be returned to 90 their initial position by a reverse operation of said plate, and means for stopping the return of the numbering wheels when each of the same assume their initial position.

33. A computing machine, comprising a plurality of numbering wheels, pinions interposed between said numbering wheels, a revolute plate, connections between said plate and numbering wheels, movably carried means associated with said pinions, means for operating said movably carried means for releasing the pinions from the numbering wheels, whereby they may be returned to their initial position upon a reversal of the operation of said plate, and means for stopping the movement of said numbering wheels as they successively reach their initial position.

34. A computing machine, comprising a suitable casing, having a sight opening, a plurality of numbering wheels revolvably mounted beneath said opening, connections between said numbering wheels whereby they are successively operated, a plate revolvably mounted in said casing and provided with a plurality of perforations exposed to view for the insertion of a stylus for operating said plate, connections between said plate and numbering wheels, a scale associated with the perforations of said plate and attached to the top of said casing, means for releasing the connections between the numbering wheels whereby they may be returned to their initial position upon a re-

versal of said plate, and means for limiting the reverse motion of said numbering wheels.

35. A computing machine, comprising a plurality of numbering wheels arranged in 5 two sets, one set serving as a register and the other set serving as a tallying device for each operation of said register, a revoluble plate, means for operating said plate and simultaneously operating both sets of numbering wheels, means for returning one set of numbering wheels by a reverse operation of said plate, and means for returning the other set of said numbering wheels.

36. A computing machine, comprising a 15 plurality of numbering wheels arranged in two sets, one set serving as a register and the other set serving as a tallying device for each operation of said register, a revoluble plate, gearing connecting said plate with 20 one set of numbering wheels, an oscillating arm overlying a portion of said plate adapted to be simultaneously operated with each operation of said plate, and connections between said arm and the other set of said 25 numbering wheels.

37. A computing machine, comprising a plurality of numbering wheels arranged in two sets, one set serving as a register, the other as a tallying device for each operation of said register, a revoluble plate provided with a plurality of perforations for the insertion of a stylus for operating said plate, gearing connecting said plate with one set of said numbering wheels, an oscillating 35 arm having its free end normally overlying the path of travel of the perforations in said plate and to be oscillated through engagement of the means for operating said plate, and connections between said arm and the 40 other set of said numbering wheels.

38. A computing machine, comprising registering mechanism, a revoluble plate, connections between said plate and said registering mechanism, a tallying device, an oscillating arm having its free end overlying 45 a portion of said plate and capable of being operated with each operation of said plate, and a ratchet and pawl connection between said arm and said tallying device.

50 39. A computing machine, comprising registering mechanism, a revoluble plate, connections between said plate and said registering mechanism, a tallying device, an oscillating arm having its free end overlying 55 a portion of said plate and capable of being operated with each operation of the plate, connections between said arm and said tallying device, an alarm, and means for sounding said alarm after a predetermined number of operations of said tallying device.

40. A computing machine, comprising registering mechanism, a revoluble plate, connections between said plate and said registering mechanism, a tallying device, an

oscillating arm having its free end overlying a portion of said plate and capable of being operated with each operation of said plate, a stop for limiting the movement given to said plate, and connections between said arm and said tallying device. 65

41. A computing machine, comprising registering mechanism, a revoluble plate, connections between said plate and said registering mechanism, a tallying device, an oscillating arm having its free end overlying 70 a portion of said plate and capable of being operated with each operation of said plate, connections between said arm and said tallying device, and an adjustable stop member for limiting the movement given to said 75 plate.

42. In a computing machine, the combination of a casing, the top of which is provided with an annular opening and with two sight 80 openings, registering mechanism under one sight opening, a tallying device under the other sight opening, a disk revolubly mounted below the annular opening, a plate containing a scale associated with said disk and attached to the top of said casing, connections between the disk and the registering 85 mechanism, and means for simultaneously operating the registering mechanism with said tallying device. 90

43. In a computing machine, the combination of a casing, the top of which is provided with an annular opening, and two sight openings, registering mechanism under one sight opening, a tallying device under the other sight opening, a disk revolubly 100 mounted below the annular opening, a plate containing a scale associated with said disk and attached to the top of said casing, connections between the disk and the registering mechanism, means for operating the 105 tallying device simultaneously with the operation of said disk, a rating chart also associated with said disk, and a stop having an adjustable relation with the rating chart and adapted to limit the movement given to 110 the disk.

44. In a computing machine, the combination of a casing, the top of which is provided with an annular opening and a sight 115 opening, a post centrally disposed below the annular opening of the casing, a disk revolubly attached to said post, and provided with a plurality of perforations for the purposes specified, a plate provided with a scale attached to the top of said casing and associated with said disk, a superposed disk also revolubly supported on said post, having its periphery spaced a short distance from the plate having the scale, registering mechanism disposed below the sight opening, connections between said first mentioned disk and said mechanism, a rating chart attached to the top of said casing, and a stop 120 125

member carried by the superposed disk and having an adjustable relation with said chart.

45. In a computing machine, the combination of a casing, the top of which is provided with an annular opening and two sight openings, a post centrally disposed below the annular opening of the casing, a plate revolubly attached to said post, and provided with a plurality of perforations for the purposes specified, a plate provided with a scale attached to the top of said casing and associated with said disk, a superposed disk also revolubly supported on said post, having its periphery spaced a short distance from the plate to expose the perforations in said disk, registering mechanism disposed below one sight opening, a tallying device disposed below the other sight opening, connections between said first mentioned disk and registering mechanism, an oscillating arm having its free end overlying a portion of the perforated disk and across and below the space between the superposed disk and plate having the scale and capable of being operated with each operation of the perforated disk, connections between said arm and tallying device, a rating chart attached to the top of the casing, and a stop attached to the superposed disk and having an adjustable relation with said chart.

46. A device for computing tonnage resistance of railway trains, comprising a casing, the top of which is provided with an annular opening and a sight opening, a post centrally disposed below the annular opening of the casing, a disk revolubly attached to said post, and provided with a plurality of perforations for the purposes specified, a plate attached to the top of the casing and provided with a scale based on a unit of rating, a superposed disk also revolubly supported on said post, having its periphery spaced a short distance from the plate having the scale, registering mechanism disposed below the sight opening, connections between said first mentioned disk and said mechanism, a rating chart attached to the top of the casing and associated with the perforated disk and scale, adapting said device for computing the tonnage resistance in trains hauled by engines of different sizes and capacity, and a stop attached to the superposed disk and having an adjustable relation with said chart.

47. A device for computing the tonnage resistance of railway trains, comprising a casing, the top of which is provided with an annular opening and two sight openings, a post centrally disposed below the annular opening of the casing, a disk revolubly attached to said post and provided with a plurality of perforations for the purposes specified, a plate attached to the top of the

casing and provided with a scale based on a unit of rating, a covering disk having its periphery spaced a short distance from the plate having the scale, to expose the perforations in said disks, registering mechanism disposed below one sight opening, a tallying device disposed below the other sight opening, connections between first mentioned disk and registering mechanism, an oscillating arm having its free end overlying a portion of the perforated disk and across and below the space between the covering disk and the plate having the scale, and capable of being operated with each operation of the perforated disk, connections between said arm and tallying device, a rating chart attached to the top of the casing and associated with the perforated disk and scale, adapting said device for computing the tonnage resistance in trains hauled by engines of different sizes and capacity, and a stop attached to the covering disk and having an adjustable relation with said chart.

48. In a computing machine, the combination of a revoluble disk, a scale associated with said disk and based on a unit of rating, a chart associated with said disk and consisting of characters denoting ratings of various engines, a member having an adjustable relation with said chart, registering mechanism, and means connecting said disk and registering mechanism, whereby the said registering mechanism will compute when the disk is moved in one direction and be returned to its initial position when the disk is moved in the opposite direction.

49. In a computing machine, the combination of a revoluble disk, a scale associated with said disk and based on a unit of rating, a chart associated with said disk and consisting of characters denoting the ratings of various engines, a member having an adjustable relation with said chart, registering mechanism, means connecting said disk and registering mechanism, whereby the said registering mechanism will compute when the disk is moved in one direction and be returned to its initial position when the disk is moved in the opposite direction, and a tallying device for indicating each forward movement of said disk.

50. In a computing machine, the combination of a revoluble disk, a scale associated with said disk and based on a unit of rating, a chart associated with said disk and consisting of characters denoting ratings of various engines, a member having an adjustable relation with said chart, registering mechanism comprising a plurality of numbering wheels, gearing connecting said disk with said numbering wheels, each forward motion of the disk causing said numbering wheels to register, and means adapted to be manually operated for placing said

numbering wheels in condition to be returned to their initial position upon backward movement of said disk.

51. In a computing machine, the combination of a plurality of numbering wheels, certain of which are provided with gears, pinions connecting the numbering wheels through the gearing thereof, means for yieldingly holding said pinions in mesh with 10 said gears, means for releasing the pinions from said gears, and a stop associated with said yielding means for limiting the return movement of the numbering wheels when they successively assume their initial position. 15

52. In a computing machine, the combination of a plurality of numbering wheels, certain of which are provided with gears, pinions connecting the numbering wheels 20 through the gearing thereof, a cradle supporting said pinions, a revolute disk operatively connected with the numbering wheels to cause them to register when moved in one direction, means for moving 25 said cradle to release the pinions from the gears of the numbering wheels to enable the return of said numbering wheels to their initial position when the operation of the disk is reversed, and means for arresting 30 the movement of the several numbering wheels when they assume their initial position.

53. In a device of the character described, registering devices, a revolute plate operatively connected with said devices, a ring like member encircling the plate and provided with a scale having designating characters, said scale serving as a guide to the operation of the registering devices by the 35 plate, the operation of the plate from points opposite the scale, adding on the registering devices, resistances equal to and at variance to and different from the amount selected for the operation of said plate.

45 54. In a computing machine, the combination of suitable registering mechanism, means for operating said mechanism, a stop for limiting the movement of the register operating means, and a numerical scale associated with the register operating means and so adjusted relatively to said stop that when 50 said register operating means is operated from points coinciding with certain designating numerals on said scale and moved to 55 the stop, said registering mechanism will add and display an amount at variance to and different from such designating numerals.

55. In a computing machine, the combination of suitable registering mechanism, a rotatable disk operatively connected with said mechanism and provided with an annular row of perforations into which may be inserted a stylus, a stop for limiting the

movement of said disk, a plate mounted in 65 juxtaposition to said disk and provided with a numerical scale, with the designating numerals thereon arranged to coincide with the perforations in the disk, the said scale so adjusted relative to the stop, that when said 70 disk is operated from points coinciding with certain designating numerals on said scale and moved to the stop, said registering mechanism will add and display an amount at variance to and different from such designating numerals. 75

56. In a computing machine, the combination of suitable registering mechanism, a rotatable disk operatively connected with said mechanism, a stop for limiting the movement of the disk, a member encircling said disk, and a numerical scale arranged on said member, said scale so adjusted relative to said stop member that the initial starting point of the scale is removed a predetermined distance from said stop, whereby when said disk is operated from points coinciding with certain designating numerals on said scale and moved to the stop, said registering mechanism will add and display an 90 amount greater than the numeral on the scale. 85

57. In a computing machine, in combination, numbering wheels registering in uniform sequence, a member having a series of 95 indicating points comprising a tonnage scale, means for operating said wheels, including means adapted to coöperate with said series of indicating points, said series 100 of points being marked by members serving as a guide in operating the numbering wheels by the operating means, and arranged so that the numbering wheels when operated by the operating means in accordance with certain indications on the scale, will register 105 an amount equal to said indications and when operated in accordance with an amount less than certain indications, will register an amount greater, and when operated in accordance with an amount greater than said 110 certain indications, will register an amount less.

58. In a computing machine, in combination, a plurality of coöperating disks, certain of which are provided with numerals 115 and serving as a register, one of said disks being the operating disk, a member associated with the operating disk and having a series of indicating points comprising a tonnage scale, said series of points being 120 marked by numbers serving as a guide in operating said disk, and arranged so that the disk when operated in accordance with certain indications on the scale will register an amount equal to said indications, and when operated in accordance with an amount less than said certain indications will register an amount greater, and when operated 125

in accordance with an amount greater than said certain indications, will register an amount less.

59. In a computing machine, in combination, a plurality of coöperating disks, certain of which are provided with numerals and serving as a register, one of said disks being the operating disk, a member associated with the operating disk and having a series of 25 indicating points comprising a tonnage scale, said series of points being marked by numbers serving as a guide in operating said disk, and arranged so that the disk when operated in accordance with certain indications on the scale will register an amount equal to said indications, and when operated in accordance with an amount less than said certain indications will register an amount greater.
- 10 60. In a computing machine, in combination, a plurality of coöperating disks, certain

of which are provided with numerals and serving as a register, one of said disks being the operating disk, a member associated with the operating disk and having a series of 25 indicating points comprising a tonnage scale, said series of points being marked by numbers serving as a guide in operating said disk, and arranged so that the disk when operated in accordance with certain indications on the scale will register an amount equal to said indications, and when operated in accordance with an amount greater than said certain indications, will register an amount less.
